UNITED STATES PATENT OFFICE

SYLVESTER L. JOINER, OF SWEETWATER, TEXAS

CROSS COUPLER DRAFT KEY RETAINER

Application filed September 24, 1931. Serial No. 564,929.

This invention relates to a cross coupler draft key retainer, and more particularly to an improvement on a locking or retaining device for all draft gear coupler cross keys.

5 One object of the invention is to provide a draft key retainer which will prevent the loss of coupler cross keys or displacement of such keys, without the use of cotter pins and U-bolts, which are now common in the art.

10 Another object of the invention is to secure the cross key in position at all times and prevent the loss of the key while the train is running at a high rate of speed.

15 Another object of my invention is to prevent the bending of the key and enable the draft gear cheek plates to wear evenly at their top and bottom.

20 Another object is to enable the draft key to kick back near the center position, so that the impact of the train will be more equalized to all of the draft gear parts.

25 A further object of the invention is to provide a simple, inexpensive device which can be manufactured at no more expense than the devices that are now in common use.

30 A still further object of the invention is to provide a retainer which will not in any way contact with the end sill of the car or draft gear parts or the center sills or the cheek plates or any rivet heads in the center sills of the draft gear attachment apertures.

35 With the above and other objects in view, a more clear understanding of my invention will be had by reference to the accompanying drawing, in which,

40 Figure 1 is a plan view, partly in section, of the center sills and draft rigging of a railroad car, with my improved key retainer attached to the draft gear key;

45 Fig. 2 is a cross sectional view on the lines 2-2 of Fig. 1; and

50 Fig. 3 is a dis-assembled view of my improved draft key retainer.

55 In the drawing, I have shown my invention as applied to the coupler or draft keys of a common type of draft gear.

60 Referring more particularly to the drawing, 1 indicates the usual coupler, and the usual center sills or beams are denoted by the numerals 2 and 3. The center sills are

provided with the usual elongated apertures 4. The numeral 5 indicates the usual yoke member of the draft rigging, and 6 indicates a common type of draft keys. It is well known that the draft keys 6 are provided at one end with a head 7 and adjacent the other end there is provided a circular aperture 8.

65 My improved draft key retainer, indicated by the numeral 9, consists of a T-bolt having an elongated fixed head 10 and a body portion indicated generally by the numeral 11. The body portion immediately below the fixed elongated head is of round formation, as indicated at 12, and below the round portion of the body 12 the body assumes a non-circular formation as at 13. There is an extension of the body portion as at 14 below said non-circular portion 13, and adjacent the end of this extension there may be provided an opening 15 for a cotter pin. In some instances it will be desirable to omit the cotter pin opening.

70 The numeral 16 indicates a detachable or removable head which functions as a retaining member. This detachable or removable head is provided with a non-circular aperture 16^a which is of the same configuration as the non-circular body portion 13. The detachable or removable head is also preferably of the same configuration as the fixed elongated head 10. A suitable nut 17 and a lock nut 18 are adapted to secure or maintain the detachable or removable head 16 in engagement with the non-circular body portion 13.

75 It will be understood that the round portion 12 of the body is adapted for insertion in the aperture 8 of the draft key. It will be seen by referring to Fig. 2 that the round portion 12 extends substantially through the opening 8 in the draft key 6 and is approximately flush with the under side of the draft key, as indicated at 19. The non-circular portion 13 projects below the under side 20 of the draft key 6 and permits the detachable or removable head 16 with its non-circular aperture 16^a to be quickly and easily inserted therein and removed therefrom. After the detachable or removable head 16 has been placed in engagement with the non-

100

circular portion 13, it is simply necessary then to run the nut 17 and the lock nut 18 on the extension, and the parts will be securely but detachably held in engagement 5 with one another. It is to be further noted that the head 10 is of a width greater than that of the round portion 12, as indicated at 21, and projects considerably beyond the circumference of the round portion 12. The 10 detachable or removable head 16 which is substantially of the same configuration as the fixed head 10, is also wider than the rounded portion 12, and projects considerably beyond the circumference thereof as indicated at 22.

While I have shown the fixed head 10 as being substantially oblong or elongated, it is to be understood that this head might be made of any suitable configuration. The 20 detachable or removable head 16 may also be made of any desired configuration. The non-circular portion 13 has been shown as of rectangular formation, but this non-circular portion may be formed oblong, triangular, hexagonal, square, or in fact it may assume any configuration other than round. The extension 14 has been shown as being threaded to receive the nuts 17 and 18, but this extension may be plain and means other 30 than the nut 17 and lock nut 18 may be used to maintain the parts in their assembled relationship.

It is desirable to have the non-circular portion of the body of the bolt of a rectangular 35 or other configuration, which will permit of the application of the detachable or removable head 16 only in true parallelism with the fixed head 10. In other words, it is desirable that the two heads of the bolt always be in true parallelism, and by having the non-circular formation of a form which will permit only of such assembling, the two heads will always be assembled in true 40 parallel relationship. The formation of the non-circular portion will prevent the detachable or removable head being assembled out of parallelism to the fixed head 10. By having the two heads of approximately the same size and configuration, in the event of the 45 retainer being kicked against the center sill, the key will always be brought back to its proper position and hold the retainer or locking means against the center sill in a horizontal position. My improved draft key 50 retainer will prevent the wear of the round portion of the body and it will always retain its true circular shape, and by having both of the heads of approximately the same size, I prevent the hole of the cross draft key from wearing oblong.

A serious objection to the prior devices of this character has been that the round portion of the bolt after considerable use wears to a non-circular formation, and with the 55 present use of cotter pins with such devices,

and due to the wear of the round portion of the bolt and its movement in the opening of the draft pin, the cotter pins are sheared off and the bolt eventually is displaced from the cross key, which often results in derailment of the cars and other serious accidents. It will therefore be readily seen that I have improved and perfected a draft key retainer which overcomes all of the disadvantages and objections to the former types of retainers for draft keys, and my invention is simple, inexpensive and durable. 70 75

It will be understood that various changes in the form, proportion, and minor details of construction, within the scope of the 80 claims, may be resorted to without departing from the spirit of the invention or sacrificing any of the advantages thereof.

What I claim is:

1. A draft key retainer comprising a 85 T-bolt having an elongated fixed head, a body portion and an elongated detachable head of substantially the same configuration as the said fixed head, said body consisting of a round portion, a non-circular portion and an extension from said non-circular portion of less width than the latter, the length of the round portion being substantially the equivalent to the thickness of the draft key and the diameter of which is less than the length of 90 the minor axis of the said heads so that when inserted in an opening in a draft key the lower portion thereof will be substantially flush with the lower surface of the draft key and the opposing surfaces of the said heads 100 will engage the upper and lower surfaces of the draft key, said detachable head being provided with an aperture opening of non-circular formation adaptable for engagement with the non-circular portion of the body and maintained substantially parallel to said fixed head, and means to maintain said detachable head in engagement with said body. 105

2. A draft key retainer comprising a T-bolt 110 having an elongated fixed head adapted for engagement with a portion of one flat side of a draft key adjacent an end thereof wherein a circular opening is provided, and a body portion, the said body portion being adapted for insertion and movement in the said opening and having its free end projecting beyond the other flat side of the draft key, and a detachable head of substantially 115 the same configuration as said fixed head provided with an opening corresponding in shape to the said projecting end of the body portion and engageable therewith, means for maintaining said detachable head on said 120 projecting end of the body, and the distance between the two heads in their assembled position being substantially the same as the thickness of the draft key. 125

3. A draft key retainer comprising a T-bolt 130 having an elongated fixed head thereon

adapted for engagement with a portion of one flat side of a draft key adjacent an end thereof wherein a circular opening is provided, and a body comprising a round portion, a non-circular portion and an extension from said non-circular portion, the said round portion of the body being dimensioned so as to substantially fill the said opening in the draft key and having the non-circular portion and its extension projecting respectively beyond the other flat side of the draft key, a detachable head of substantially the same configuration as said fixed head provided with an opening corresponding in shape to the said non-circular portion of the body and engageable therewith, means for maintaining said detachable head on the body, and the distance between the two heads in their assembled relationship being substantially the same as the thickness of the draft key.

4. A draft key retainer comprising a T-bolt having an elongated fixed head adapted for engagement with a portion of one flat side of a draft key adjacent one end thereof wherein a circular opening is provided, and a body portion, the said body consisting of a round portion, a non-circular portion and an extension from said non-circular portion, the round portion being of a size to substantially fill the said opening and the length of which is substantially the equivalent of the thickness of the draft key and having the non-circular portion and the extension projecting respectively beyond the other flat side of the draft key, a detachable head of substantially the same configuration as said fixed head provided with an opening engageable

with said non-circular portion and maintained substantially parallel to said fixed head, means on said extension to maintain said detachable head in engagement with said body, and the distance between the two heads in their assembled relationship being substantially the same as the thickness of the draft key.

5. A draft key retainer comprising a T-bolt having an elongated fixed head adapted for engagement with a portion of one flat side of a draft key adjacent one end thereof wherein a circular opening is provided, and a body portion, the said body consisting of a round portion adaptable for insertion and movement in the said opening in the draft key, said round portion being of a length substantially the equivalent of the thickness of the draft key, a non-circular portion on the said body extending from the round portion and an extension of said body from said non-circular portion of less width than the latter, and a detachable head of substantially the same configuration as said fixed head provided with an opening of non-circular formation engageable with said non-circular portion and maintained substantially parallel to said fixed head, means to maintain said detachable head in engagement with said body, and the distance between the two heads in their assembled relationship being substantially the same as the thickness of the draft key.

In testimony whereof I have hereunto set my hand, this 24th day of September, 1931.
